(57) **CLAIM**

The ornamental design for a convector, as shown and described.

DESCRIPTION

1.-2. Convector

FIG. 1.1 is a perspective view of a convector, showing our new design;

FIG. 1.2 is side elevation view thereof;

FIG. 1.3 is another side elevation view thereof;

FIG. 1.4 is a bottom plan view thereof;

FIG. 1.5 is a top plan view thereof;

FIG. 1.6 is front elevation view thereof;

FIG. 1.7 is a rear elevation view thereof;

FIG. 2.1 is a perspective view of a convector, showing the second embodiment our new design;

FIG. 2.2 is side elevation view thereof;

FIG. 2.3 is a another side elevation view thereof;

(Continued)

FIG. 2.4 is a bottom plan view thereof;
 FIG. 2.5 is a top plan view thereof;
 FIG. 2.6 is front elevation view thereof; and
 FIG. 2.7 is a rear elevation view thereof.
